(57) **CLAIM**

The ornamental design for the toaster with mini cooker, as shown and described.

DESCRIPTION

FIG. 1 is a perspective view of the toaster with mini cooker showing my new design,

FIG. 2 is a front elevation view thereof,

FIG. 3 is a right elevation view thereof,

FIG. 4 is a left elevation view thereof,

FIG. 5 is a back elevation view thereof,

FIG. 6 is a top plan view thereof; and,

FIG. 7 is a bottom view thereof.

Features shown in broken lines are shown for environment only and do not form a part of the design claimed.
